WILSON D. ALTHOUSE, OF PHILADELPHIA, PENNSYLVANIA.

METHOD OF AND APPARATUS FOR SEPARATING COAL AND LIKE SUBSTANCES AND IMPURITIES MINGLED THEREWITH.

Application filed August 22, 1922. Serial No. 583,629.

To all whom it may concern:

Be it known that I, WILSON D. ALTHOUSE, a citizen of the United States, residing at Philadelphia, in the county of Philadelphia and State of Pennsylvania, have invented certain new and useful Improvements in Methods of and Apparatus for Separating Coal and like Substances and Impurities Mingled Therewith, of which the following is a specification.

This invention consists in a novel method of and apparatus for separating slate and bone or bone-coal from pure coal, through the aid of a moving air current.

Briefly stated, the method consists in introducing mingled coal, slate and bone or bone-coal, advisably reduced to lumps or cubes of about one inch or less in cross section, into an ascending air column of force sufficient to lift and carry with it all particles of lower specific gravity than that of slate, which is about 1.90, the slate falling out of the ascending column and being led away; next deflecting the air current sharply and at the same time admitting a regulated additional supply of air, whereby the volume of air is increased and the velocity is reduced, thus permitting the bone or bone-coal, which has a specific gravity of about 1.45 to 1.65, to fall from the air current through a second ascending air column, while the pure coal, of a specific gravity of about 1.35, is carried onward to a pipe or separating chamber of larger diameter, and delivered into a third ascending air column, through which the pure coal is permitted to fall by reason of the reduced velocity of the current. Each pipe or chamber after the first is, preferably, furnished at its lower end with an automatic valve to prevent ingress of air at such points, and consequent disturbance or variation of pressure from that required at any given point or points in the system.

The accompanying drawing illustrates a preferred form of apparatus by which the process may be carried out and will aid in explaining such process, but it is to be understood that the drawing illustrates only one embodiment or form of apparatus for the purpose. In other words, the principle or mode of separation may be utilized in or through the use of apparatus differing considerably from that illustrated.

Referring to the drawing, the numeral 1

indicates a feed hopper which receives the mixed coal, bone, or bone-coal and slate to be treated, and delivers the same into a horizontal conveyor pipe or trunk 2, containing a conveyor 3 here shown as of spiral form, the shaft 4 of which carries a wheel 5 through which rotary motion may be transmitted by belt or otherwise from any prime mover. The discharge end of the conveyor pipe or trunk opens into an upright pipe or separating chamber 6, open at its lower end, and communicating at its upper end with a horizontal pipe or conduit 7 provided with a valve 8, preferably of the gate type, and applied to the end of the pipe, though these latter details are unimportant. Pipe or conduit 7 opens into or communicates with a second upright pipe or separating chamber 9, which should be of at least as large diameter or capacity as the chamber 6 and conduit 7, and may be slightly larger. This pipe or chamber 9 is provided at its lower end with a self-closing valve 10, or equivalent and usual means for practically preventing ingress of air, while allowing egress of any solid product falling downward in or through said pipe.

The upper end of pipe or chamber 9 is provided with a T or short three-branched pipe section 11, flanged at both ends, and sealed at one end by a removable cap-plate or closure 12. Said pipe or chamber 9 is also formed or furnished with a branch or Y 13, which connects and communicates with one end of a T 14 similar to T 11, and the other end of which is connected by a suitable coupling 15 with the unsealed end of T 11, so that chamber 9 is placed in communication with the T 14 at the lower and upper ends thereof. The lateral branch of T 14 communicates by a pipe or conduit 16, advisably of somewhat greater cross-sectional area than pipe 9, with a third upright pipe or separating chamber 17, provided at its lower end with an automatic valve 18, and connected at its upper end with a pipe or extension 19 which leads to the eye of an exhaust fan 20, or equivalent suction device of high power.

Pipe or chamber 9 is provided below the Y 13 with a lateral branch 21, which may be closed or opened to any desired extent by a valve 22 of any suitable type.

The apparatus being thus constructed and valves 8 and 22 being wholly or partially

closed, hopper 1 is supplied with the mingled coal, slate and bone or bone-coal to be treated, and the conveyor 3 and exhaust fan 20 are caused to operate at suitable speeds.

5 The conveyor delivers the mixture in a steady stream to pipe or chamber 9, and the suction fan causes a current of air to flow through the connecting pipes or conduits, and produces in each of the separating 10 chambers 6, 9 and 17 an ascending column of air. If now there be discharged through the open lower end of pipe or chamber 6 a quantity of the heaviest of the several substances, slate, closely approximating its 15 known percentage in the volume of mixture passing, valve 8 is left as adjusted. If the discharge be less than the known slate-content percentage, the valve 8 is opened somewhat, thus admitting air at that point, increasing the volume of the air-current and 20 reducing its velocity, and consequently reducing its lifting or carrying capacity. By gradually increasing or diminishing the opening of the valve 8 as indications require, 25 the air current can be so regulated as to permit all the clear slate, or matters of approximately 1.90 specific gravity, to fall through the ascending air column of chamber 6, while all matters of appreciably lower specific 30 gravity will be carried upward through said chamber and delivered into pipe or chamber 9. A second and similar separation takes place in pipe or chamber 9 between substances of approximately 1.45 to 1.65 specific 35 gravity, such as impure coal, bone-coal, and bone, and that or those of appreciably or materially lower specific gravity, chiefly or wholly pure coal which, as stated, is of about 1.35 specific gravity.

40 The bodies or matters of 1.45 specific gravity and higher will descend through and be discharged from pipe or chamber 9, while those of appreciably lower specific gravity will ascend said pipe or chamber, 45 and pass by T 14 and conduit 16 to the larger upright pipe or chamber 17. It will be noted that pipe or chamber 9 communicates with T 14 both by the Y 13 and by T 11, while valve 22 being below the Y 13, admits air to pipe or chamber 9 near its lower end and some distance below the point at 50 which conduit 7 communicates with said pipe or chamber 9.

The result of this arrangement is that air 55 in quantity controlled by valve 22, adjusted in accordance with the discharge from chamber 9, as previously explained with reference to chamber 6 and valve 8, is drawn into the lower portion of pipe or chamber 60 9 while the air column rising through chamber 6 and entering through valve 8, enters the upper part of chamber 9. The air entering through valve 22 in ascending, alone meets matters falling through chamber 9, 65 and taking the more direct route afforded by

the Y 13 has little or no effect on the air entering the upper part of pipe or chamber 9, this latter current being thus left to perform the duty of carrying over into pipe or conduit 16 and upright pipe or chamber 17, the 70 pure coal, or products of specific gravity below 1.45.

This arrangement of air pipes and chambers permits the velocity of the air column ascending through the lower portion of pipe or chamber 9 to be accurately regulated and determined by proper adjustment of valve 22, practically unaffected by the air leaving the upper part of said chamber 9 and passing 75 to conduit 16.

The larger cross section of pipe or chamber 17 as compared with that of pipe or chamber 9 and conduit 16, permits the air entering it to expand, increasing its volume and lessening its velocity, thus permitting 80 all matters having a specific gravity materially below 1.45 to fall through the pipe or chamber 17, while the air passing to the exhaust fan carries only the dust and lighter floating matters.

In practice it has been found expedient or advantageous to make the pipes or chambers 6 and 9 of about fourteen inches internal diameter, the pipe or conduit 16 of about sixteen inches internal diameter, and the pipe or chamber 17 and extension 19 of 85 about twenty inches internal diameter, but these dimensions and proportions may be varied at will within somewhat wide limits.

90 So, too, as above stated, it is found that better results are attainable if the coal be brought to a size of approximately one cubic inch before treatment in the apparatus; but here again it is permissible and practicable to depart from the specific size stated, and to 95 treat coal of larger or smaller dimensions. So far, however, as practical use of the process and apparatus has yet indicated, the several dimensions proposed are deemed the best for general adoption and use.

100 The abrupt change of direction of flow of the air current at each point where the coal or coal and other matters enter a separating chamber or upright pipe, is found a matter of importance, and a 90 degree change in the conduit is here indicated at such points. A cleaner and sharper separation is effected with this than with a less abrupt change of flow, because the air and lighter matters change their direction somewhat readily and hence follow the generally upward or forward flow of the air, while the heavy matters cannot do so and accordingly are carried downward through the force of gravity.

105 In the drawing the weighted valves are suggestive merely, and may be replaced by any common or well known form of outlet closure capable of being practically sealed against ingress of air by a rather small accumulation of product, yet permitting es- 110 115 120 125 130

cape of product when such accumulation reaches a given point. Many such closures or valves are common in the art, and the weighted valve is merely a type thereof, used 5 for convenience and simplicity of illustration.

The term pure coal is used to indicate coal which is as nearly pure as the better grades of cleaned or picked coal, though it may 10 and usually does contain a percentage of impurities.

The removable cap or closure 12 is provided to facilitate clearing the conduit 7 or the separating chamber 9 in case of need. 15 Man-holes and valves may of course be provided at suitable points throughout the system.

It is obviously immaterial so far as the ultimate result, that is, the cleaning or separation of coal and its attendant impurities is concerned, how the air current is produced, whether by suction or by blast or pressure. The suction fan as here illustrated is found to be efficient and economical, but so long as an air current of adequate velocity and volume be produced and made controllable both as to velocity and as to volume, the apparatus will be effective, and the process may be carried out.

30 It is possible also by properly varying the cross sectional area of the different separating chambers, to secure reasonably close separation without the use of the valves 8 and 22, but their use is deemed highly admirable not only because securing closer separation, but also because affording a wider range of use of the apparatus, or its use with a wider range of products differing in percentage and relative specific gravity of their 40 component elements or constituents.

In the practical use of the apparatus it is found that in addition to effecting a remarkably clean separation of the pure and impure product, it causes a drying of wet or damp coal. This is quite advantageous in that it insures ascertainment of the true weight of the coal and, coupled with the removal of practically all dust, etc., from the coal, enables the producer or seller to base 45 estimates and contracts upon a definitely ascertainable wastage.

What I claim is:—

1. The method of separating pure coal from impurities of greater specific gravity 55 than the coal but mingled therewith, which consists in subjecting the mingled coal and impurities to the lifting and carrying action of an air current caused to form successive ascending and confined columns of successively lower velocity, each column of force 60 sufficient to carry upward and onward the mixture treated, except the content thereof having the greatest specific gravity of the several constituents entering any given column, and thereby progressively dropping

out of the air current at different points the impurities, and finally, the pure coal.

2. The method of separating pure coal from impurities of greater specific gravity than the coal but mingled therewith, which 70 consists in subjecting the mingled coal and impurities to the lifting and carrying action of an air current caused to form successive ascending and confined columns of successively lower velocity and greater volume, each column of force sufficient to carry upward and onward the mixture treated, except the content thereof having the greatest specific gravity of the several constituents entering any given column, and thereby progressively dropping out of the air current at different points the impurities, and finally, the pure coal.

3. Apparatus for separating coal and impurities mingled therewith, comprising a 85 pipe system or conduit having a plurality of vertical chambers with discharge openings at their lower ends; closures for said openings, adapted to open under weight of predetermined accumulation of material in 90 the chambers; means for causing a continuous flow of air through the conduit and chambers; and means for varying and controlling the ingress of air at suitable points in the system, and thereby making the lifting power of the air currents in the several chambers progressively less.

4. Apparatus for separating coal and impurities mingled therewith, comprising a 100 pipe system or conduit having a plurality of vertical chambers with discharge openings at their lower ends and of successively larger cross section; closures for said discharge openings, adapted to open under weight of predetermined accumulation of 105 material in the chambers; means for causing a continuous flow of air through the conduit and chambers; and means for introducing into the first chamber of the series a continuous stream of the mingled coal and 110 impurities, the conduit connecting the several chambers and serving to carry from each to the next the product less the impurities already removed.

5. Apparatus for separating coal and impurities mingled therewith, comprising a 115 pipe system or conduit having a plurality of vertical chambers with discharge openings at their lower ends and of successively larger cross section; closures for said discharge openings, adapted to open under predetermined accumulation of material in the chambers; means for causing a continuous flow of air through the conduit and chambers; and means for varying and controlling the ingress of air at suitable points in the system, and thereby apportioning the lifting and carrying capacity of the ascending column of air in each chamber to the specific 120 gravity of the materials therein treated.

6. The herein described apparatus for separating coal and its impurities, comprising a pipe system or conduit and means connected with said system and serving to cause a constant flow of air therethrough in one general direction; upright chambers included in said system, having discharge openings at their lower ends and successively of larger cross section; closures for the discharge openings of said chambers adapted to permit escape of coal and impurities but to prevent material ingress of air; valves for admitting air to the pipe system or conduit and one or more of the chambers, to control the velocity and the volume of air therein; and means for supplying the mingled coal and impurities to the first of said chambers, the connection between the several chambers and the conduit being made at approximately a right angle.
7. The herein described apparatus for separating coal and impurities mingled therewith, comprising a pipe system or conduit and three upright chambers included in or

in communication with said conduit, said chambers having discharge openings at their lower ends; means connected with said conduit for causing a continuous flow of air therethrough and upward through the several chambers; a feed hopper; means for delivering material from said feed hopper to the first chamber; a valve for opening the conduit to the atmosphere, or partially or wholly closing the air inlet at a point above the first chamber; a valve for permitting and controlling ingress of air to the lower portion of the second or intermediate chamber, said second chamber communicating with the third by a pipe or conduit section through a passage below and a passage above the top of the first chamber and the pipe connecting said chamber with the second; and means for excluding material ingress of air but permitting discharge of coal through the discharge openings of the chambers other than the first.

In testimony whereof I have signed my name to this specification.

WILSON D. ALTHOUSE.
